UNITED STATES PATENT OFFICE.

FRANÇOIS MAURON, OSKAR SEITZ, AND JULIUS JONAS, OF BADEN, SWITZERLAND.

MOLECULAR VACUUM PUMP.

Application filed February 20, 1926. Serial No. 89,531.

This invention relates to pumps for deriving a high vacuum, particularly those of the rotary type.

The general object of the present invention is the provision of a pump construction which will be effective to obtain a high vacuum with increased efficiency.

Other and further objects will be pointed out or indicated hereinafter, or obvious to one skilled in the art upon an understanding of the present disclosure.

In the drawing forming a part of this specification are presented two illustrative structures embodying the invention, but it is intended that the invention may take other and divers forms all within the scope of the appended claims.

In the drawing,—

Fig. 1 is a face view of the rotating pump member,

Fig. 2 is a sectional elevation of one pump construction, and

Fig. 3 is a sectional elevation of another pump construction.

For an understanding of the invention reference may be made immediately to the illustrative forms wherein reference character *a* designates a rotating disc provided with spiral flanges *a'* to form intervening channel ways *b*. The top margins of the flanges *a'* are all in a common plane but the body portion of the disc is slightly dished so that the channel ways decrease in cross sectional area from the centre outwardly.

On the frame *s* is formed the pump housing *p* in which the disc *a* is mounted for operation being carried on the shaft of the rotor *h* of an electric motor, said shaft being supported in the bearings *k*. Mounted within the pump housing *p* for contact with the top margins of the flanges *a'* is the stationary disc *c* which affords an axial conduit *d* for admission of air to the space between the discs. The frame *s* carries the motor housing portion *g* in which is supported the stator *f* of the motor, said housing being hermetically closed by the casing cover *g'*.

The pump housing affords the outlet *e* from the channel *k* which circumscribes the circumference of the disc *a*. The disc *c* is preferably made of a suitable self-lubricating material which is competent to withstand the rubbing action of the flanges *a'* and to sustain the pressure of the disc *a*. As

a means for maintaining the desired contact between the flanges *a'* and the disc *c*, the rotor *h* may be displaced to a slight extent off of the magnetic centre position of the field, in an axial direction away from the disc *a*, so that the magnetic pull of the field will be effective to urge the disc *a* towards the disc *c*. The conduit *d* is connected with the receiver, and the outlet *e* with the primary vacuum pump. The entire pump and motor casing is hermetically tight, thus permitting the desired freedom of play in the bearings *k*.

In the embodiments shown in Fig. 3, the disc *a* is supported on a vertical axis instead of a horizontal axis, and provided with a cover plate *m* in lieu of the disc *c*. The cover plate *m* has a tubular axial extension *m'* which projects into a circular channel *r* in the bottom cover plate, said channel being filled with mercury to provide a hermetic seal, the weight of the disc *a* and the rotor having support on a thrust bearing *q*.

Among the other advantages possessed by this construction is that of having three or all of the walls of the air extracting member movable, whereby an additional air impelling force is obtained. A further advantage resides in a reduction of the clearance losses. A pump of this description is adapted for continuous and high speed operation and is effective to obtain a high degree of vacuum.

What we claim is:

1. A pump, including two discs, one of which has a plane surface, and the other of which is spirally grooved and has a concave surface in the grooves and a plane surface between the grooves, which latter surface is in contiguous association with the plane surface of the first described disc.

2. A pump, including two discs, one of which has a plane surface, and the other of which has a number of spirally extending flanges which vary in height from the center to the periphery of the disc and terminate outwardly therefrom in coplanar surfaces for contiguous association with the plane surface of the first described disc.

3. A pump, including two discs, one of which is stationary and has a plane surface, and the other of which is rotatable and has a number of spirally extending

flanges which vary in height from the center to the periphery of the disc and terminate outwardly therefrom in coplanar surfaces for sliding contact with the plane surface of the first described disc.

4. A pump, including two relatively rotatable discs between which is formed a spirally extending channel-way, means for rotating one of the discs, and means tending 10 to press the discs together during such rotation.

5. A pump, including a rotating centrifugally acting conveyor having a drive shaft, a hermetic closure for the conveyor and 15 shaft, and an electric motor having the rotor portion thereof mounted on the shaft and

the stator portion thereof mounted on the inside of the closure.

6. A pump, including a rotating centrifugally acting conveyor having a drive shaft, 20 a hermetic closure for the conveyor and shaft, and an electric motor having the rotor portion thereof mounted on the shaft and the stator portion thereof mounted on the inside of the closure in axially offset 25 relation to the rotor.

In testimony whereof we have hereunto subscribed our names at Zurich, Switzerland, on the 28th day of January A. D. 1926.

FRANÇOIS MAURON.

OSKAR SEITZ.

JULIUS JONAS.
